UNITED STATES PATENT OFFICE.

FREDERICK JULIUS KALDENBERG, OF TARRYTOWN, NEW YORK, ASSIGNOR
TO M. S. KALDENBERG, OF SAME PLACE.

TOBACCO-PIPE.

SPECIFICATION forming part of Letters Patent No. 552,711, dated January 7, 1896.

Application filed March 6, 1893. Serial No. 464,856. (No model.)

To all whom it may concern:

Be it known that I, FREDERICK JULIUS KALDENBERG, a citizen of the United States, residing at Tarrytown, in the county of Westchester and State of New York, have invented certain new and useful Improvements in Tobacco-Pipes, of which the following is a specification.

My invention relates to pipes for smokers' use, and the object of the invention is, in part, to provide an improved means for admitting air in regulated quantities to the smoke-passage in the stem so as to cool the smoke, and in part to provide a convenient construction whereby the nicotine distilled from the burning tobacco may be collected and prevented from getting into the smoke-passage in the stem.

The invention will be fully described hereinafter, and its novel features carefully defined in the claims.

In the accompanying drawings, which serve to illustrate my invention, Figure 1 is a longitudinal section of a briarwood pipe embodying my improvements, and Fig. 1^a is a transverse section through the stem thereof on the line 1^a 1^a in Fig. 1. Fig. 1^b is a detached perspective view of the metallic screw which connects the sections of the bowl. Fig. 2 represents the mouthpiece and core detached, and Fig. 2^a is an end view of the core. Fig. 3 illustrates a slightly different construction of the core, the view being a longitudinal section of the stem, core, mouthpiece, and a part of the bowl.

Referring primarily to the principal figures, and particularly Figs. 1 and 2, A represents, as a whole, the bowl of a pipe, which will be, by preference, of briarwood, or some wood with a figured grain, and B the stem of the pipe formed integrally with the bowl. The bowl A is cut across transversely at x, this cut forming an upper section a, forming a receptacle for the tobacco, and a lower section a^x, forming a receptacle for the nicotine. The stem B is connected with this lower section a^x. In the upper part a is the cavity a' to receive the tobacco or other substance or mixture to be smoked, and the bottom of this cavity is pierced to form a passage or passages a² for

the smoke to pass down into a cavity a³ in the lower part a^x of the bowl on its way to the smoke-passage in the stem.

It is desirable in wooden pipe-bowls, having a figured grain, that the upper and lower parts of the bowl shall appear by the closeness of the joint and the continuity of the figured grain to be integral, and in order to carry out this feature I first shape the bowl and stem of the pipe in the usual way and excavate the bowl to form the cavity a'. I then cut the bowl transversely along the line x as smoothly as possible, and afterward form the cavity a³. To secure the upper and lower sections of the bowl together, a screw (see at y in Fig. 3) is formed in the wall of the cavity a³, and a screw-threaded metal ring or tube-section a⁴ (seen detached in Fig. 1^b) is set tightly in the base of the upper section of the bowl in position to screw down into the cavity 70 in the lower section of the same, as seen in Fig. 1. If necessary, the outer surface of the bowl may be dressed and finished after the sections are screwed together, so as to remove any roughness about the joint due to inaccuracy in fitting.

In the cavity a³ a wad of cotton w may be placed to receive and absorb the nicotins, and this cotton may carry chemical substances designed to neutralize the nicotine.

C is the mouthpiece of the stem, and D is a core attached to said mouthpiece and designed to occupy a bore in the stem B. Figs. 1, 1^a, 2 and 2^a illustrate the preferred manner of constructing this core with a view to the admission of air in regulated quantities to the smoke-passage in the core and mouthpiece. In these views the main portion or body of the core D is cylindrical, and is adapted to fit snugly into the main bore in the stem B. At 90 its end is a short cylindrical portion d, which is eccentric to the body and is adapted to enter and fit a counterbore in the stem, which counterbore connects the main bore therein with the cavity or chamber a³ in the lower section of the bowl. The core D has a longitudinal slit d^x in it, which adapts the core to fit expansively and tightly in the main bore of the stem when inserted, somewhat in the manner of a split key. In the lower side of the 100

- core is formed a channel d' , and in its upper side is formed a channel d^2 . These channels communicate at a point near the mouthpiece with the smoke-passage c . The upper channel d^2 extends to the end of the reduced portion d of the core, and forms a smoke-passage to lead the smoke from the bowl to the passage c ; and the lower channel d' forms an air-passage, which will be hereinafter described.
- 10 It will be seen that the wall of the bore in the stem B forms one wall of the respective smoke and air passages, the channels d' and d^2 being open grooves in the core. These grooves may be much more cheaply and conveniently formed than holes bored in the core and extending through the same longitudinally, and as the nicotine will collect mainly in them it may be readily cleaned out when the core is withdrawn.
- 15 20 The influx of air to the channel d' may be regulated by the device clearly illustrated in Fig. 1. A hole e is bored in the under side of the stem near the bowl, and this hole communicates with the channel d' . In the hole e is fitted a screw-plug g , in which is an air-passage h . When the plug is screwed in home the entry of air to the passage h is cut off. Any known device of this character may be employed, that shown being preferred.
- 25 30 Fig. 3 shows a construction slightly different from that already described. The part d is omitted from the core D , and the core is not slotted longitudinally. Otherwise there is no material difference.
- 35 40 The construction of the core with the part d insures its proper insertion in the stem, and the slit insures a snug fit in the bore of the stem.
- It will be seen by inspection that while the large bore in the stem of the pipe is open both to the bowl and the air-inlet the core, when inserted, interposes a barrier between said air inlet or passage and the passage leading from the bowl to the groove d^2 , thus compelling the smoke and air to traverse the respective grooves in the core to the point where they unite with the smoke-passage c .
- 45 50 Of course I do not limit my invention to wooden pipes; but in many respects it is well adapted to this class of pipes.

Having thus described my invention, I claim—

1. In a pipe, the combination with the stem having a relatively large bore which communicates at its inner end with the bowl of the pipe and has, at its inner end, near the bowl an air-inlet, and means substantially as described for regulating the influx of air at said inlet, of a mouthpiece having in it a smoke-passage, and a core D , secured to said mouthpiece and adapted to fit snugly in the enlarged bore in the stem, said core having two longitudinal passages, d' and d^2 , both communicating at their outer ends with the smoke-passage in the mouthpiece, the former communicating at its front end with the air-inlet to the stem, and the latter communicating at its front end with the bowl of the pipe, substantially as set forth.

2. In a pipe, the combination with the stem, having a relatively large bore which communicates at its inner end with the bowl of the pipe and by a lateral passage in the stem with the air, and a mouthpiece having in it a smoke-passage, of a core D , secured to said mouthpiece, said core having a short cylindrical portion d , which projects beyond the main portion into the bowl, and said core having also two separate passages, d' and d^2 , for the air and smoke, respectively, which passages connect at a point near the mouthpiece with the smoke-passage therein.

3. The combination with the stem and bowl of a pipe, said stem having in it a relatively large longitudinal bore, communicating at its inner end with the bowl and by a lateral passage, with the air, of the mouthpiece, and the core, D , secured to said mouthpiece, said core having a longitudinal slit d' , two oppositely arranged longitudinal grooves, d' and d^2 , and a smoke-passage c , with which said channels communicate, as set forth.

In witness whereof I have hereunto signed my name in the presence of two subscribing witnesses.

FREDERICK JULIUS KALDENBERG.
